UNITED STATES PATENT OFFICE.

JACOB FOX, OF NEW YORK, N. Y.

BUTTON.

1,111,452.

Specification of Letters Patent. Patented Sept. 22, 1914.

Application filed September 19, 1911. Serial No. 650,262.

To all whom it may concern:

Be it known that I, JACOB FOX, a citizen of the United States, residing at New York, in the county of New York and State of New York, have invented certain new and useful Improvements in Buttons, of which the following is a specification.

This invention relates to improvements in buttons, and particularly to that type of button combining a textile-covered face with a metal or like collet or back. Heretofore this type of button has been constructed with what is commonly called the tufted shank, the forming of which is a tedious, expensive and not altogether satisfactory method, as the tufted portion varies in shape in the different buttons and does not always afford a proper means of attaching the button to a garment.

The invention aims to provide a button, easily, quickly and therefore cheaply assembled, and having a resilient metal shank which shall afford a firm means of securing the button to a garment, the shape of the shank being substantially uniform in all the buttons.

A further object is to provide a button having separable portions, namely, a front and a collet or back, said portions being held in detachable engagement by a resilient looped shank secured to the front, the loop being passed through an aperture in the back and held there by its resiliency, thus providing a means of attaching the button to a garment.

Further objects will appear in the following description; it being understood that changes in form, proportion, and minor details of construction may be resorted to within the scope of the appended claim.

For a full understanding of the invention and the merits thereof, reference is to be had to the following description and accompanying drawing, in which:

Figure 1 is a perspective view of the completed button; Fig. 2 is a vertical sectional view of the same; Fig. 3 comprises a perspective view of the various parts of the button before assembling the same.

Corresponding and like parts are referred to in the following description and indicated in all the views of the accompanying drawing by the same reference characters.

The improved button embodies a concavo-convex back or collet 1, formed of ivory, celluloid, metal or the like, and provided with a preferably elongated slot 2, centrally

disposed to said collet and adapted to receive an attaching means for the button. Mounted in the concaved side of the collet 1 are the cup-shaped clamping members 3 and 4 which provide a front to the button and are preferably formed from relatively soft sheet metal. The inner clamping member 3 is provided with an aperture 5 through which passes the bifurcated end of a contracted metal shank 6, the members 7 forming said end being bent back into engagement with the concaved side of the clamping member. The other end of the shank 6 forms a resiliently compressible loop or eye 8, substantially circular in form and joining onto the contracted shank 6. Said loop being compressed and forced through the aperture 2 in the collet 1, thereafter expands, engages the walls of said aperture and secures the front and collet of the button in detachable engagement. The eye 8 further provides a means of attaching the button to a garment. Inserted in the concaved side of the clamping member 3 and covering the angular members 7 of the shank, is a pad 9, of the usual type, which forms a packing therein. The clamping member 4 is slightly larger than the member 3 and its convexed face is covered with fabric 10, which is doubled inwardly beyond the margin or flange of the member 4 so that when the clamping members 3 and 4 are forced together the fabric is gripped between the two and securely held. The pad 9 now forms a stop to the angular end of the shank 6 and also prevents the deformation of the clamping members if they are subjected to a blow. The fabric 10 between the coacting edges of the clamping members 3 and 4 is further secured when the margin of the outer member 4 is forced inwardly to firmly grip the member 3. Up to this point in its construction, the button presents a relatively smooth, finished appearance which is readily completed by the insertion of the resilient shank 6 in the aperture 2 of the collet 1 on the concaved side thereof, so that the eye 8 is compressed and forced through said aperture and expands on the convexed side of the collet 1 where it engages the walls of the aperture 2 and secures the front and the collet of the button in assembled position and also provides means for attaching the button to a garment.

It will here be noted that the margin of the concaved side of the collet 1 is substantially perpendicular to the back there-

of; furthermore, the circumferential surface of the fabric covered portion which engages said margin is formed of alternating portions of cloth and metal which gives 5 resiliency to said surface. When the eye 8 is forced through the aperture in the collet 1 the fabric covered portion engages the margin of the collet and being resilient is slightly compressed and thus firmly 10 engages and conforms closely to the shape of the margin of the collet. This holds the two detachable portions of the button securely together and if the resilient eye 8 should become deformed in shape so as 15 not to resiliently engage the collet, the parts would nevertheless be held together by virtue of the inter-engagement of the fabric covered portion with the margin of the collet. This is of advantage to prevent 20 loss or separation of the parts when the button is not attached to a garment. Moreover, the accumulation of dirt between the parts of the button is effectually prevented as the parts fit tightly together and the 25 fabric covered portion substantially fills the concavity of the collet.

It will be readily seen that the separable construction permits the fabric bearing portion of the button to be removed from the 30 collet and cleaned as is very often desirable, since dirt and foreign matter collects between the fabric and the collet. Furthermore the covered portion may be removed and the fabric readily replaced should it 35 become worn, or should it be desired to change its color.

It will here be noted that the flange of the lower clamping member 3 extends upwardly and outwardly, while the upper 40 clamping member 4 is larger than the lower member and the flange thereof extends downwardly and inwardly so that, when the clamping members are assembled, the fabric covering 10 will be effectually clamped 45 between the flanges of said members and also between the flange of the upper member and the inner wall of the collet. It will also be noted that the circumferential edge of the fabric covering 10 projects above 50 the upper edge of the flange of the lower member 3 and is thence extended across the top of said flange and rests on the upper surface of the pad 9, the circumferential edge of the fabric covering 10 being forced 55 or pressed into the upper surface of the pad 9 when the parts are assembled. By this construction, a four-point contact or clamping action on the fabric covering 10 is produced, first between the inner wall 60 of the collet and the flange of the upper clamping member, second between the lower edge of the flange of the upper clamping member and the collet, third between the

adjacent walls of the flanges of both members, and fourth between the lower surface 65 of the top of the member 4 and the upper surface of the pad 9.

Attention is called to the ease with which the button may be assembled in comparison with the button using the tufted shank, entirely dispensing with the use of dies and other tools which are necessary in the construction of the tufted shank type. Moreover the results are not always the same with the latter type as the tufted shank is 70 frequently mutilated in the process of forming it, so that it is difficult and in some cases impossible to pass a needle through the shank in mounting the button for use. On the other hand the resilient shank of 75 the button of this invention makes the assembling of the parts simple and the results uniform and positive, as a firm, neat eye is provided on each button so that it may be mounted for use with ease. 80

Having thus described the invention, what is claimed as new is:

A button comprising a concavo-convex collet having an opening in the bottom thereof, co-acting upper and lower cup-shaped clamping members of different sizes seated in the concave body of the collet, the lower clamping member partially closing the opening in the collet and being provided with an upwardly and outwardly extending flange and the upper clamping member being larger than the lower clamping member and provided with a downwardly and inwardly extending flange overlapping the flange of the lower clamping member, a rigid shank extending through the opening in the collet and having oppositely disposed arms bearing directly against the upper face of the lower clamping member, a pad entirely filling the space between said clamping members, and a covering extending over the top of the upper clamping member and having its marginal edge extended downwardly between the inner wall of the collet and the outer wall 100 of the flange of the upper clamping member and thence extended upwardly between the flanges of both clamping members and thence laterally above the upper edge of the flange of the lower clamping member 105 and in contact with the upper surface of the pad, the extreme circumferential edge of the covering being pressed into the pad by engagement with the inner face of the upper clamping member. 110

In testimony whereof I affix my signature in presence of two witnesses:

JACOB FOX. [L. S.]
